Patented May 12, 1903.

UNITED STATES PATENT OFFICE.

ROBERT S. WIESENFELD, OF BALTIMORE, MARYLAND.

DESIGN FOR AN ADVERTISING-CLOCK CASE.

SPECIFICATION forming part of Design No. 36,319, dated May 12, 1903.

Application filed January 21, 1903. Serial No. 140,086. Term of patent 7 years.

To all whom it may concern:

Be it known that I, ROBERT S. WIESENFELD, a citizen of the United States, residing at Baltimore city, State of Maryland, have invented a new, original, and ornamental Design for an Advertising-Clock Case, of which the following is a specification, reference being had therein to the accompanying drawing, forming part thereof.

My new, original, and ornamental design consists of a casing for advertising-clocks, as shown in the accompanying drawing. Resting upon the base is a gradually-tapering framework consisting of corner-strips and transparent sides. A central post extends from the base to the upper portion of the clock-frame and passes through a series of

shelves or supports. At the upper portion of the clock-frame a central panel extends, upon either side of which is a plain panel with ornamental bases, and a central space below. A circular aperture for the clock-dial is arranged in the front of the frame, and below said aperture a rectangular panel is arranged.

Having thus fully described my invention, what I claim is—

The ornamental design for an advertising-clock case as shown and described.

In testimony whereof I have affixed my signature in the presence of two witnesses.

ROBERT S. WIESENFELD.
